Wm. Walter Owen, Atty:

UNITED STATES PATENT OFFICE

SIMEON C. LAWLOR, OF CHICAGO, ILLINOIS

WINDOW POLE

Application filed January 4, 1929. Serial No. 330,322.

My invention relates in general to a window pole, and more specifically to an improved pole of the type used in opening and closing windows and one which has been designed to have a greater range of usefulness than the present type of pole now generally in use.

One feature of the invention is to provide a pole of small dimensions which is useful not only in office buildings and schools, etc., but also in homes, apartments and hotels.

Another feature is a pole which is completely protected by rubber bumpers at all points so as to prevent injury to polished surfaces and to prevent breakage of windows which so often occurs with the present poles.

Another feature is a pole designed and adapted so that it may be used to lower the upper sash of a window without using the usual hole in the upper part of the window frame, but merely by engaging the lower part of the frame.

Other features and objects such as cheapness of construction will be pointed out in the following detailed description.

Referring to the drawings:

Figure 1 is a side view of my improved window pole with the handle broken in the center;

Fig. 2 is a view taken from the top in Fig. 1;

Fig. 3 is a sectional view of the upper part or head of the pole disclosed in Figs. 1 and 2 taken along the line 3-3 of Fig. 2;

Fig. 4 is a diagram illustrating how the pole may be used on an ordinary window to raise or lower the upper sash;

Fig. 5 is a view of a modified form of my invention showing the same applied to an ordinary walking stick for demonstration purposes.

Referring now to Fig. 1, I show a wooden handle 2 broken in the center to show that it may be of greater length. A grip 3 is either formed on the wooden handle from the wood itself, or is applied in the form of a rubber grip. On the upper end of the pole is a brass sleeve 4 riveted to the handle by a rivet 5. This sleeve is preferably a piece of brass tubing and has a pair of round drilled holes

6 and 7 registering with a hole through the wood handle as shown in Fig. 3.

A piece of brass rod or tubing 8 is inserted through the holes in the handle and held rigidly in place by a rivet 9. This rod is straight and short at one end somewhat to the ordinary projection on window poles and on the opposite side is curved downward with a somewhat wide curve, thus presenting a prong which is farther from the handle at the lower end than the width of the usual window frame. On the opposite ends of the rod 8, I provide rubber tips 10 and 11 which are somewhat similar to a cane tip and are slipped over the end of the rod.

The upper end of the wooden handle projects somewhat above the end of the brass sleeve 4 and is grooved around the top as shown in Fig. 3. Into this groove is inserted a rubber ring 12 to prevent the end of the pole damaging any surface or breaking the window glass. The left-hand or short end of rod 8 has a pair of grooves or indentations 13 and 14, one on its upper and one on its lower surface, so that if desired the rubber tip may be removed and this end of rod 8 used as an ordinary window pole to be inserted into the hole which is usually present in the upper part of a window frame, as illustrated at 15 in Fig. 4.

The object of forming the rod 8 as shown with this particular wide curve is so that it may be used first as shown at A in Fig. 4. That is, this prong is hooked over the upper part 16 of the frame of the lower sash without touching it and pressed against the frame of the upper sash at 17. Thus it may be seen that the upper sash may be readily lowered about an inch or so, depending on the length of the prong made by rod 8. After thus lowering the sash the pole is reversed as shown at B in Fig. 4, and the short prong is used to lower the sash further if desired.

In Fig. 5, I have shown the principles of my invention applied to an ordinary walking stick which has a curved upper portion or handle 18 closely approximating the curve of the rod 8, as shown in Fig. 1, and provided with a projecting part 19 which consists of a length of brass tubing clamped around the

shaft and held together by a screw or rivet 20. This projection may also be provided with a rubber tip as is the rod 8, Fig. 1. I have shown the walking stick as jointed at 21 in the well known manner and it will thus be seen 5 that this form of the invention may be carried in a traveling bag if desired and used as a regular window pole or cane, as desired.

From the foregoing it will be seen that I 10 have designed a very useful window pole for opening or closing windows which is very simple to use and economical to manufacture. Also, I have provided a pole which is very 15 adaptable to any type of window for either upper or lower sash and one which may be used with a minimum amount of effort and wear or damage to the windows.

Having fully described and ascertained the 20 features and aspects of my invention, what I consider to be new and desire to have protected by Letters Patent will be pointed out in the appended claims.

What is claimed is:

1. A window pole comprising a handle, a 25 brass sleeve riveted over one end of the handle, a rod inserted through holes in the sleeve and handle, one end of the rod forming a straight projection and the other a curved hook, said rod rigidly fastened to the handle.
2. A window pole comprising a handle, a 30 pair of metal projections secured to one end of the handle, one comprising a short straight prong and the other formed into a curved hook which is wider than the thickness of a 35 window frame and curved downward sufficient to permit an upper casement of a window to be lowered a certain distance by engaging said prong with the lower edge of the frame thereof, and rubber cushions for each 40 projection and for the end of the pole.

In witness whereof, I hereunto subscribe my name this 31st day of December, A. D. 1928.

SIMEON C. LAWLOR.
